Primary Examiner — Paula Greene(74) *Attorney, Agent, or Firm* — Seed IP Law Group PLLC(57) **CLAIM**

The ornamental design for a handle, as shown and described.

DESCRIPTION

FIG. 1 is an isometric projection of an embodiment of a handle of my new design.

FIG. 2 is a top plan view of the handle of FIG. 1. The bottom plain view is the mirror image.

FIG. 3 is a right side elevational view of the handle of FIG. 1. The left elevational view is the same; and, FIG. 4 is a front elevational view of the handle of FIG. 1, a rear elevational view is the same.
